UNITED STATES PATENT OFFICE

2,471,165

FANCY TRIMMING STITCH

Jack Nachman, Philadelphia, Pa.

Application July 1, 1946, Serial No. 680,808

2 Claims. (Cl. 2—244)

1

My invention relates to fabric and relates particularly to a method and means for creating an ornamental series of stitches which will produce the eye effect of binding.

Heretofore, bindings for ornamental goods have been made but it is a purpose of my invention to provide a series of threads sewn and arranged in such a manner as to create the effect of an ornamental binding.

It is, therefore, an object of my invention to sew and lay on a fabric a series of stitches as well as a plurality of threads which give the eye appeal of a binding.

Other objects of my invention are to provide an improved device of the character described, that is easily and economically produced, and which is sturdy in construction.

With the above and related objects in view, my invention consists in the details of construction and combination of parts, as will be more fully understood from the following description, when read in conjunction with the accompanying drawing in which:

Fig. 1 is an ornamental view showing a thread of my invention.

Fig. 2 is a sectional view taken along the lines 2—2 of Fig. 1.

Referring now in greater detail to the drawings embodying my invention wherein similar reference characters refer to similar parts, I show a piece of fabric, generally designated as A, on which the effect of a binding is to be created to the eye and in which different ornamental designs may be made.

A thread 16 is laid in a zig-zag or sine-wave fashion upon the surface of the fabric A. Upon the surface of the fabric A and beneath the upper portion of the thread 16 is a tape or cord 12 laid in a straight line. Along each side of the tape or cord 12 is a series of stitches 10 and 14. Each of the stitches 10 and 14 hold a portion of the zig-zag thread 16 to the fabric A so that the zig-zag thread is tacked to the fabric and a portion of the zig-zag thread 16 holds the tape or cord 12 in contact with the fabric A.

It should be noted that with respect to the longitudinal central axis of the zig-zag thread 16 the design created is symmetrical, one portion being designated the upper portion and the other the lower portion.

2

The series of stitches 10 is located adjacent the curved upper portion of the zig-zag thread 16 with the tape or cord located adjacent the stitches 10 and the stitches 14.

5 It is to be noted that the inlaid thread or tape 12 is held by spaced cross thread portions 16A, 16B and the other portions of the zig-zag thread 16 are tacked or sewn to the fabric by stitches 10, 14. A sewing machine may be altered to do the stitching, to lay the inlaid thread, and to lay the zig-zag or sine-wave thread in position.

Symmetrically placed with respect to the longitudinal axis of the zig-zag thread 16 and at the lower portion of the thread 16 is a second tape, or 15 cord, or inlaid thread 22 held by the portions 16A and 16B of the lower portion of the zig-zag thread 16 and between the parallel row of stitches 20 and 24. The second tape 22 with its complementary stitches 20 and 24 is similar in position to the tape 12 and the upper rows of stitches 10 and 14.

20 The color effect or a varied color effect can be created by making the row of stitches 10 and 14 of one color, 12 a second or a different color than the thread for the stitches, the zig-zag or 25 sine wave thread 16 may be a third color or the same color as the other threads. The rows of stitches 20 and 24 may be made of different colors or they may be of a color similar to the stitches 30 10 and 14, thereby creating a novel and ornamental effect on the fabric.

35 Although my invention has been described in considerable detail, such description is intended as being illustrative rather than limiting, since the invention may be variously embodied, and the scope of the invention is to be determined as claimed.

I claim as my invention:

1. An ornamental tape effect created by a series 40 of stitches wherein a zig-zag or sine-wave shaped thread is laid upon a piece of fabric, the upper and lower portions of said thread being held by a series of parallel stitches, and a straight tape or cord overlying the top of the fabric and lying 45 beneath the upper and lower portions of said zig-zag or sine-wave thread and between the plurality of rows of stitches at the upper and lower portions.

2. An ornamental tape effect created by a series 50 of stitches upon a fabric wherein a zig-zag or

sine-wave shaped thread is laid upon said fabric, a plurality of straight tapes or cords, the upper portion of said thread lying upon one of said straight tapes, a series of straight stitches parallel to one another and tacking said thread to said fabric, and having said upper tape between said parallel straight stitches, and a second straight tape or cord between a series of straight stitches at the lower portion of said thread, said upper and lower tapes or cords being symmetrically arranged with respect to a longitudinal axis. 10

JACK NACHMAN.
